(57) **CLAIM**

The ornamental design for an ankle brace, as shown and described.

DESCRIPTION

FIG. 1 is a perspective view of the ankle brace showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and, FIG. 10 is a partial enlarged view of portion 10 in FIG. 1. The even-length broken lines are for illustrating portions of the ankle brace that form no part of the claimed design. The dot-dash broken lines in FIGS. 1, 9, and 10 are for indicating the location of the FIGS. 9 and 10 enlarged views on FIG. 1, and also form no part of the claimed design.
